RECEIVER CIRCUITS

Bernardus D. H. Tellegen, Eindhoven, Netherlands, assignor, by mesne assignments, to Radio Corporation of America, New York, N. Y., a corporation of Delaware

Application September 27, 1939, Serial No. 296,717
In the Netherlands October 15, 1938

7 Claims. (Cl. 250—20)

This invention relates to a circuit arrangement for accentuating either the carrier wave with respect to the side-bands, or the side-bands with respect to the carrier wave of an amplitude-modulated oscillation.

In some cases it is necessary that the side-bands of an amplitude-modulated oscillation should be accentuated with respect to the carrier wave. Such case occurs, for example, with test oscillators, in which an amplitude-modulated oscillation must be generated with a modulation depth of 100% and with a very low distortion of the modulation. For this purpose it is frequently desirable that the generated oscillation should first be modulated with a very low modulation depth, say 10%, and that then the modulation depth should be increased by accentuating the side-bands with respect to the carrier wave. This may be effected, for example, with the aid of very sharp filters, in particular crystal filters. In other cases it is necessary that the carrier wave of an amplitude-modulated signal should be accentuated with respect to the side-bands, for which purpose also use may be made of crystal filters.

The use of crystal filters for the above-mentioned purposes is very expensive. Moreover, due to the fixed tuning frequency of crystal filters the latter can be used only for a single carrier-wave frequency. Another disadvantage inherent in the use of crystal filters is that the carrier wave of the oscillation, of which the modulation depth must be influenced, must be maintained constant with great accuracy, for which purpose in many cases a complicated and accurately operating device for automatic frequency correction is required.

The present invention has for its purpose to provide a circuit arrangement for influencing the modulation depth of an amplitude-modulated oscillation, in which the above mentioned disadvantages are avoided.

According to the invention, use is made of a network constituted by the parallel-connection of a rectifier operating with peak detection, of which the output impedance for alternating currents of the modulation frequencies is substantially different from the output resistance for direct current, and an oscillatory circuit which is tuned to the carrier-wave frequency.

The amplitude-modulated oscillation of which the modulation depth must be influenced, can be fed to this network in different manners. According to one embodiment of the invention, the network has a current supplied to it which is

proportional to the oscillation of which the modulation depth must be influenced, which may be effected, for example, by interposing the network in the anode circuit of an amplifying tube of high internal resistance, to the control grid of which tube is fed the said oscillation.

According to another embodiment of the invention, a voltage proportional to the oscillation of which the modulation depth must be influenced, is induced in the oscillatory circuit which is connected in parallel with the rectifier.

The output voltage of the circuit arrangement may be constituted either by the voltage produced across the network or by the voltage produced across a self-inductance coil which is inductively coupled to the oscillatory circuit connected in parallel with the rectifier. In both of these cases the output impedance of the rectifier for alternating currents of the modulation frequencies must be given a low value for accentuating the carrier wave, and for accentuating the side-bands it must be given a high value with respect to the output resistance for direct current.

25 The output voltage of the circuit arrangement can also be derived from a second oscillatory circuit which is tuned to the carrier wave frequency and inductively coupled to a self-inductance coil which is connected in series with the rectifier. In this case the output impedance of the rectifier for alternating currents of the modulation frequencies must be given a high value for accentuating the carrier wave, and for accentuating the side-bands it must be given a low value with respect to the output resistance for direct

30 current.

35 The output impedance of the rectifier is preferably constituted either by the parallel-connection of an ohmic resistance and a condenser, of which the impedance for alternating currents of the modulation frequencies is small with respect to the said resistance, or by the series-connection of an ohmic resistance and a choke coil, of which the impedance for alternating currents of the modulation frequencies is great with respect to the said resistance.

40 According to another feature of the invention, the blocking resistance of the oscillatory circuit which is connected in parallel with the rectifier, is given a high value with respect to the output resistance of the rectifier for direct current, which may be achieved, for example, by undamping the oscillatory circuit by means of feed-back coupling.

45 In contradistinction with the known filters,

the network used according to the invention has the particular feature of being always automatically tuned to the carrier-wave frequency of the signal supplied. This feature permits of using the circuit arrangement according to the invention for suppressing amplitude variations of oscillations modulated in phase or in frequency, for which purpose so far use has always been made of limiters.

The invention will be more clearly understood by reference to the accompanying drawings showing, by way of example, different embodiments according thereto in Figs. 1 to 7 inclusive.

Fig. 1 shows an amplifier tube 1 of high internal resistance. The oscillation, of which the modulation depth must be influenced, is fed to terminals 2 and 3 which are connected respectively to the control grid and the cathode of the tube 1. The anode circuit of the tube 1 is consequently traversed by a current which is proportional to the oscillation supplied. The anode circuit comprises a network which is constituted by the parallel connection of an oscillatory circuit 4 which is tuned to the carrier-wave frequency of the oscillation supplied, and a diode 5 operating with peak detection. A condenser 6 is provided in series with the diode 5, which condenser has a low impedance for the carrier wave frequency and a high impedance for the modulation frequencies, and constitutes a parallel connection with the output impedance 7, of which the ohmic resistance is much different from the impedance for alternating currents of the modulation frequencies. The voltage produced across the described network is supplied to output terminals 9 and 10 through a condenser 8.

The operation of the circuit arrangement is as follows: As can be demonstrated by calculation, the impedance for the carrier wave frequency of a rectifier operating with peak detection, to which is fed an amplitude-modulated signal, is equal to half the output resistance of the rectifier for direct current, whereas for an arbitrary side-band frequency the impedance is equal to half the output impedance of the rectifier for the modulation frequency corresponding to this side-band frequency. A rectifier operating with peak detection, of which the output impedance for alternating currents of the modulation frequencies is substantially different from the output resistance for direct current, consequently behaves in relation to an amplitude-modulated signal supplied to the rectifier, as a bi-pole, of which the impedance for the carrier wave frequency is much different from the impedance for the side-band frequencies. In other words it behaves as a bi-pole containing a resonant circuit which is very sharply tuned to the carrier wave frequency, that is to say a parallel resonant circuit in the event that the output impedance of the rectifier for alternating currents of the modulation frequencies is small, and a series resonant circuit in the event that the output impedance of the rectifier for alternating currents of the modulation frequencies is great with respect to the output resistance for direct current. The network interposed in the anode circuit of the tube 1 consequently has for the carrier wave frequency an impedance which is substantially different from the impedance for the side-band frequencies so that a voltage will be produced across this network, of which the modulation depth is substantially different from that of the current supplied to the network.

The current flowing through the rectifier 5

comprises a large number of harmonics of the carrier wave frequency. To ensure a satisfactory operation of the circuit arrangement, it is, therefore, necessary that the impedance of the rectifier circuit for the generated harmonics is low with respect to the impedance for the carrier wave frequency. Otherwise voltages with the frequency of one or more of the harmonics are produced at the terminals of the rectifier, which disturb satisfactory operation of the rectifier. This condition is satisfied by the presence of the oscillatory circuit 4 which has a high impedance for the carrier wave frequency, but a very low impedance for the harmonics of the carrier wave frequency. In the circuit arrangement illustrated in Fig. 1, the direct current voltage is applied to the anode of the tube 1 through the coil of the circuit 4. A disadvantage of this manner of feeding is that the cathode of the diode 5 is at a high potential with respect to ground which may lead to difficulties in the supply of heating current for the diode.

Fig. 2 shows a circuit arrangement in which this disadvantage is obviated by using parallel feeding with the aid of a choke coil 11 and a blocking condenser 12. Moreover, in the circuit arrangement of Fig. 2 the output impedance of the rectifier 5 is constituted by a resistance 13, with which the series connection of a large condenser 14 and a resistance 15 is connected in parallel. The resistance 15 is small with respect to the resistance 13 so that the output impedance of the diode 5 for alternating currents of the modulation frequencies is low with respect to the output resistance for direct current. Consequently, the diode 5 behaves for the supplied oscillations as a bi-pole containing a parallel resonant circuit which is very sharply tuned to the carrier-wave frequency so that the impedance of the network interposed in the anode circuit of the tube 1 is considerably greater for the carrier wave frequency than for the side-band frequency. Consequently, a voltage will be produced across the circuit 4, of which the modulation depth is much smaller than that of the oscillation fed to the terminals 2, 3. A voltage with a correspondingly decreased modulation depth is induced in the coil 16, which is inductively coupled to the circuit 4, and supplied to the output terminals 9 and 10. By means of this circuit arrangement the carrier wave of the supplied oscillation is accentuated with respect to the side-bands.

Since a voltage is produced across the circuit 4, of which the modulation depth is smaller than that of the anode current of the tube 1, the current supplied to the circuit 4 will also exhibit a smaller modulation depth. Consequently, the current flowing through the diode 5 will exhibit a greater modulation depth than the anode current of the tube 1, which may lead to difficulties if the voltage fed to the terminals 2 and 3 is modulated very deeply. In fact, in this case an over-modulation of the current flowing through the diode 5 could be produced with the result that the voltage produced across the condenser 6 would be considerably distorted, thus disturbing the correct operation of the diode 5. This inconvenience can be eliminated by giving the blocking resistance of the circuit 4 a high value with respect to the output resistance for direct current of the diode 5. In fact, it is thus ensured that practically no current flows through the circuit 4 so that the whole anode current of the tube 1 is led through the diode 5, and the current flowing through the diode 5 consequently

cannot have a greater modulation depth than the anode current. This condition can be satisfied, for example, by reducing the damping of the circuit 4 by means of feedback coupling, as is shown in detail in Fig. 3.

In the circuit arrangement of Fig. 3, which also serves to accentuate the carrier wave with respect to the side-bands, the output impedance of the diode 5 is constituted by the parallel connection of a resistance 13 and a condenser 17, which latter condenser exhibits a very low impedance for alternating currents of the modulation frequencies, this in contradistinction with the usual rectifier circuit arrangements, in which the condenser 17 has a high impedance for alternating currents of the modulation frequency. While in the usual rectifying circuit arrangements the condenser 17 usually has a capacity of the order of 100 mmf., the capacity of the condenser 17 in a circuit arrangement of Fig. 3 may be approximately 1 mf. A very high blocking resistance of circuit 4 is obtained by a positive feed-back coupling with the aid of a coil 18 which is inductively coupled to the circuit 4 and interposed in the control grid circuit of the tube 1 in series with the terminal 2 and 3.

For accentuating the carrier wave with respect to the side-bands, use may also be made, without objection, of the circuit arrangement of Fig. 4 when a positive feedback coupling is used for undamping the oscillatory circuit 4, said circuit arrangement being distinguished from the arrangement of Fig. 3 in that the diode 5 and condenser 17 are mutually exchanged. This circuit arrangement in itself has the disadvantage that the circuit 4 is more strongly damped by the resistance 13. This inconvenience can be eliminated, however, by increasing the feedback coupling.

Fig. 5 shows a circuit arrangement, by means of which the side-bands of an amplitude-modulated signal can be accentuated with respect to the carrier wave and by means of which, for example, the modulation depth of a signal which is fed to the terminals 2 and 3 and modulated very slightly, can be increased up to 100%. The oscillation, of which the modulation depth must be increased, is fed to the network 4, 5 by inducing in the circuit 4 a voltage which is proportional to this oscillation. This is effected by coupling this circuit inductively to an oscillatory circuit 21 which is interposed in the anode circuit of the tube 1. As in the arrangement of Fig. 3, the output impedance of the diode 5 is constituted by the parallel connection of a resistance 13 and a condenser 17 of great capacity. The blocking resistance of the circuit 4 has been given a lower value, however, so that the diode 5 is traversed by a current, the modulation depth of which is considerably greater than that of the anode current of the tube 1. The output voltage is derived from an oscillatory circuit 19 which is tuned to the carrier wave frequency and is inductively coupled to a coil 20 of low inductance which is arranged in series with the diode 5. As already mentioned, the current flowing through the diode comprises a large number of harmonics of the carrier-wave frequency which are suppressed, however, by the circuit 19 to such an extent that practically no harmonics are fed to the output terminals 9 and 10.

Fig. 6 represents another circuit arrangement for accentuating the side-bands with respect to the carrier wave of an amplitude modulated sig-

nal, in which use is made of a rectifier operating with peak detection, of which the output impedance for alternating currents of the modulation frequencies is great with respect to the output resistance for direct current. In fact, the output impedance of the diode 5 is constituted in this arrangement by the parallel connection of a resistance 13 and a choke coil 22 with which a resistance 15 is connected in series. The choke coil 22 has a very high impedance for alternating currents of the modulation frequencies, but a low direct current resistance, while also the resistance 15 is low with respect to the resistance 13. Consequently, the output impedance of the diode 5 for alternating currents of the modulation frequencies is great with respect to the output resistance for direct current so that the rectifier for the oscillation fed to the terminals 2 and 3 behaves as a bi-pole comprising a series resonant circuit which is sharply tuned to the carrier wave frequency. The condenser 6 in this circuit arrangement acts as in the circuit arrangements of Figs. 1 and 2, as a low impedance for the carrier wave frequencies, but as a high impedance for alternating currents of the modulation frequencies. As in the circuit arrangement of Fig. 5, the oscillation, of which the modulation depth must be increased, is fed to the network 4, 5 by inducing in the circuit 4 a voltage which is proportional to this oscillation, the circuit 4 being inductively coupled to a coil 23 which is interposed in the anode circuit of the tube 1. Furthermore, it can be mentioned that the resistance 13 is directly connected in parallel with the circuit 4, with the result that this circuit will be rather strongly damped. In the present circuit arrangement this does not involve great difficulty, however, since it is not necessary to satisfy the condition that the blocking resistance of the circuit 4 is high with respect to the output resistance of the diode 5 for direct current.

In conclusion, Fig. 7 represents a circuit arrangement in which the output impedance of the rectifier 5 for alternating currents of the modulation frequencies is high with respect to the output resistance for direct current, but in which the carrier wave is accentuated with respect to the side-bands. The output impedance of the diode 5 is constituted by the series connection of a resistor 15 and a choke coil 22, of which the impedance for alternating currents of the modulation frequencies is great with respect to the resistance 15. The condenser 6 constitutes a high impedance for alternating currents of the modulation frequencies. As in the circuit arrangement of Fig. 6, the diode 5 behaves for the oscillation fed to the terminals 2 and 3 as a series resonant circuit which is sharply tuned to the carrier wave frequency. If the blocking resistance of the circuit 4 is not given too high a value, the diode 5 will be traversed by a current of which the modulation depth is smaller than that of the anode current of the tube 1 so that an alternating voltage of small modulation depth can be derived from the terminals 9 and 10.

As may appear from the foregoing the network used according to the invention has the particular feature that it behaves as a resonant circuit which is automatically tuned exactly to the carrier wave frequency. With respect to the use of crystal filters this feature offers the important advantage that an accurately operating device for correcting the carrier wave frequency can be dispensed with. Moreover, said

feature creates the possibility of using the circuit arrangement according to the invention for suppressing amplitude variations of oscillations which are modulated in phase or in frequency, for which purpose use may be made, for example, of one of the circuit arrangements of Figs. 2, 3, 4 and 7. The oscillations of variable amplitude which are modulated in phase or in frequency are fed in this case to the terminals 2 and 3, whereas oscillations with the same phase- or frequency modulation but with a substantially constant amplitude may be taken from the terminals 9 and 10. Instead of a diode, use may also be made of another rectifier with two electrodes, for example, a dry rectifier.

What is claimed is:

1. In combination with an electron discharge tube having input and output electrodes, said input electrodes being adapted to have signal-modulated carrier voltage applied thereto, a signal-modulated carrier voltage output network coupled to the output electrodes, a second network connected between the output electrodes for controlling the effective percentage modulation of the applied modulated carrier voltage comprising a peak detection rectifier and a resonant circuit, said resonant circuit being tuned to the carrier frequency, a resistor element in a closed series circuit with said rectifier and resonant circuit, said resistor element being free of rectified currents therethrough and providing an impedance for alternating currents of the modulation frequencies which is substantially different from the resistance for direct current, and said output network utilizing the controlled modulated carrier voltage developed across said resonant circuit.

2. In combination with an electron discharge tube having input and output electrodes, said input electrodes being adapted to have signal-modulated carrier voltage applied thereto, a signal-modulated carrier voltage output network coupled to the output electrodes, a second network connected between the output electrodes for controlling the effective percentage modulation of the applied modulated carrier voltage comprising a peak detection rectifier and a resonant circuit arranged in parallel with each other, a resistor element in a closed series circuit with said rectifier and resonant circuit, said resistor element being free of rectified currents therethrough and providing an impedance for alternating currents of the modulation frequencies which is substantially different from the resistance for direct current, said resonant circuit being tuned to the carrier frequency, and said output network utilizing the controlled modulated carrier voltage developed across said resonant circuit.

3. In combination with an electron discharge tube having input and output electrodes and having a relatively high internal resistance, said input electrodes being adapted to have signal-modulated carrier voltage applied thereto, a signal-modulated carrier voltage output network coupled to the output electrodes, a second network connected between the output electrodes for controlling the effective percentage modulation of the applied modulated carrier voltage comprising a peak detection rectifier and a resonant circuit, said resonant circuit being tuned to the carrier frequency, a resistor element in a closed series circuit with said rectifier and resonant circuit, said resistor element being free of rectified currents therethrough and providing an

impedance for alternating currents of the modulation frequencies which is substantially different from the resistance for direct current, and said output network utilizing the controlled modulated carrier voltage developed across said resonant circuit.

4. In combination with an electron discharge tube having input and output electrodes, said input electrodes being adapted to have signal-modulated carrier voltage applied thereto, a signal-modulated carrier voltage output network coupled to the output electrodes, a second network connected between the output electrodes for controlling the effective percentage modulation of the applied modulated carrier voltage comprising a peak detection rectifier and a resonant circuit, said resonant circuit being tuned to the carrier frequency, and said output network utilizing the controlled modulated carrier voltage developed across said resonant circuit, said rectifier including in circuit therewith a load resistor, and the impedance of said load for alternating currents of modulation component frequencies being different than the ohmic resistance thereof.

5. In combination with an electron discharge tube having input and output electrodes, said input electrodes being adapted to have signal-modulated carrier voltage applied thereto, an output network coupled to the output electrodes, a second network connected between the output electrodes comprising a peak detection rectifier and a resonant circuit, said resonant circuit being tuned to the carrier frequency, and said output network utilizing the modulated carrier voltage developed across said resonant circuit, and means for reactively coupling said resonant circuit to said input electrodes thereby to provide feedback to the latter.

6. In a signal-modulated carrier voltage transmission system of the type having carrier voltage input terminals and output terminals; the improvement which comprises a network connected between the output terminals for controlling the effective percentage modulation of the applied modulated carrier voltage and which has a substantially different impedance for the carrier frequency than for the modulation component frequencies, said network including a resonant circuit tuned to said carrier frequency, reactive means regeneratively coupling said resonant circuit to said input terminals, and a diode rectifier circuit operatively associated with said resonant circuit, said rectifier circuit comprising a load element whose impedance for modulation component frequency currents is different from its ohmic resistance.

7. In a signal-modulated carrier voltage transmission system of the type having carrier voltage input terminals and output terminals; the improvement which comprises a network connected between the output terminals for controlling the effective percentage modulation of the applied modulated carrier voltage and which has a substantially different impedance for the carrier frequency than for the modulation component frequencies, said network including a resonant circuit tuned to said carrier frequency, means reactively coupling said resonant circuit to said input terminals, and a diode rectifier circuit operatively associated with said resonant circuit, said resonant circuit having a high impedance for currents of carrier frequency, but a low impedance for harmonics of the latter.
